UNITED STATES PATENT OFFICE.

ROBERT F. PIERCE, OF COLLINGSWOOD, NEW JERSEY, ASSIGNOR, BY MESNE ASSIGNMENTS, TO CHARLES M. HORTER, OF PHILADELPHIA, PENNSYLVANIA.

LIGHTING-FIXTURE.

1,305,234.

Specification of Letters Patent. Patented May 27, 1919.

Application filed June 1, 1915. Serial No. 31,370.

To all whom it may concern:

Be it known that I, ROBERT F. PIERCE, a citizen of the United States, residing in Collingswood, Camden county, State of New Jersey, have invented certain new and useful Improvements in Lighting-Fixtures, of which the following is a specification.

- One of the objects of my invention is to provide a lighting fixture including a novel arrangement of the light reflecting and diffusing members in relation to the light source whereby the widest and most efficient distribution of light upon the ceiling of a room may be obtained.
- 15 A further object is to so combine and arrange the light reflecting and diffusing members or bodies with respect to the light source that the rays of light emanating therefrom strike the surfaces of such members at the smallest practicable angle whereby a more efficient redirection or reflection of the light rays is obtained.

Although the fixture embodying my invention is especially suitable and adapted for use in shops, laboratories and industrial plants generally, yet it is also suitable for use in dwellings, public halls, etc., and it is a further object of my invention that the construction shall be simplified and cheapened so that its use may become general.

Other objects and advantages of my invention will be referred to in the detailed description thereof which follows or will be apparent therefrom.

In the accompanying drawings I have illustrated one constructional form of my invention but it will be understood that changes in the construction may be made 40 within the scope of the claims without departing from my invention.

In the drawings:—

Figure 1 is a side elevation of a fixture embodying my invention;

45 Fig. 2 is a top plan view of the same; and Fig. 3 is a view partly in vertical section and partly in side elevation of the same.

Referring to the drawings, 1 designates a pipe or conduit through which electric wires 50 extend to a socket 2. The conduit 1 usually depends from a ceiling or other wall and at its point of emergence from such ceiling or wall is provided with and surrounded by a shield or skirt 3. 4 designates an electric light bulb which engages the socket 2. 5 des-

ignates the incandescent filament of said electric light, said filament constituting the source of light. For the purpose of diffusing and reflecting the light I have provided the slightly concavo-convex diffusing and reflecting member 6 which is suspended directly underneath the electric light, the center thereof being substantially directly underneath the source of light, namely, the incandescent filament 5. The edges of the reflecting and diffusing member 6 extend a considerable distance laterally of the said light as shown in the drawings. Said member 6 preferably is translucent or semi-transparent so that portions of the light pass therethrough while other portions are reflected from the surface thereof. The said member 6 is supported by means of chains 10, three of which are employed, although it will be understood that the number may be changed if desired. The lower ends of the chains are provided with elongated rods or links 11 having hooks 12 at their lower ends which detachably engage the outer edges of the member 6 and support the same as is apparent from the drawings.

In the construction shown it will be observed that the outer edges of the member 6 are situated in a horizontal plane which extends a short distance below or outside of the source of light at 5.

15 designates a supplemental or secondary reflecting member which has an opening 16 at its center the edges of which are, in the construction shown, substantially in alignment with the lower end of the light source. The reflecting member 15 is of annular shape and is inclined from the edge 16 upwardly and outwardly and is provided with holes 17 through which the links or rods 11 extend. It will be understood that the upper ends of these links are passed through the opening 17 before the eyes 18 thereof are formed.

The member 15 may consist of any suitable material, as metal, having its upper surface polished or provided with a coating of suitable material whereby such upper surface becomes a reflecting surface or the said member 15 may be constructed as the member 6 of semi-transparent or translucent material. The member 15 is supported in proper position upon the rods or links 11 by means of flange-like projections 20 thereon. The upper ends of the chains 10 are 110

connected with hooks 21 which are secured upon the shield or skirt 3 previously referred to.

It will be observed that the position of the outer edges of the member 6 with respect to the source of light at 5 and with respect to the lower edge of the annular member 15 is such that the rays of light which emanate from the source at 5 and pass underneath the lower edge 16 of the annular member 15 and which do not impinge upon the member 6 extend outwardly very nearly in a horizontal direction so that they will not pass directly to the eyes of any one who may be in a room lighted by my fixture.

It will also be observed that the relation of the members 6 and 15 with respect to the source of light at 5 is such that the rays of light from said source strike the surfaces of the said members at the smallest practicable angles with the result that a more efficient reflection of the rays is obtained.

Certain of the rays which impinge upon the upper surface of the member 6 are reflected against the under side of the member 15, which under side is also a reflecting surface, from which surface certain of the rays are reflected outwardly into the room while others are reflected back against the member 6 and finally pass out into the room in which the fixture is located.

Of course, the angles at which the rays from the light source 5 impinge upon the member 6 vary at different points increasing as the center is approached at which a central ray from the light source 5 is perpendicular to the opposing surface of the member 6.

Instead of an electric light a gas or oil light may be employed.

The members 6 and 15 may be of any other suitable shape or contour which may be preferred to the shapes shown.

I claim:—

1. A light fixture comprising a source of light, an annular reflecting member, the inner edge of said annular member being situated in a plane passing in proximity to the lower edge or end of said light source, a light reflecting and diffusing member situated below the said light the outer edges of which extend beyond the outer edges of the said annular reflecting member and being nearly horizontal and in substantial parallel relation to said annular reflecting member, and means common to the said members for supporting the same in operative relation to the said light.

2. In a light fixture in combination a light emitting element, a substantially horizontal light reflecting and diffusing member supported underneath the said light, a substantially horizontally arranged annular light reflecting member supported above the first named member and having its inner edge practically in the plane of the lower end of said light emitting element, said element extending upwardly from said plane and said annular member being inclined upwardly and outwardly from its inner edge, means for supporting the said members, said means including rod-like members extending through the said annular reflecting member and being provided with means underneath the same for supporting it and being provided with means at their outer ends for engaging and supporting the first named reflecting member, substantially as described.

In testimony that I claim the foregoing as my invention I have hereunto signed my name this 29 day of May, A. D. 1915.

ROBERT F. PIERCE.

In the presence of—

C. E. KLEINFELDER,
FLORENCE DEACON.
